UNITED STATES PATENT OFFICE.

GEORGE W. BEADLE, OF BAYONNE, NEW JERSEY, ASSIGNOR TO SINGLE SERVICE PACKAGE CORPORATION OF AMERICA, OF NEW YORK, N. Y., A CORPORATION OF NEW JERSEY.

PAPER-CARTON-MAKING MACHINE.

1,112,351.

Specification of Letters Patent. Patented Sept. 29, 1914.

Application filed August 2, 1911. Serial No. 641,916.

To all whom it may concern:

Be it known that I, GEORGE W. BEADLE, a citizen of the United States, residing at Bayonne, in the county of Hudson and State of New Jersey, have invented certain new and useful Improvements in Paper-Carton-Making Machines; and I do hereby declare the following to be a full, clear, and exact description of the invention, such as

10 will enable others skilled in the art to which it appertains to make and use the same.

This invention relates to the manufacture of tubes for paper cartons or vessels, and has for its object to produce a machine 15 which will make such tubes from a strip of paper after cutting it into suitable lengths, wind said paper into form while gluing the parts together, print upon the paper, so it will appear upon the tube in its proper position, any desired legend, and one which will 20 then close the end of the tube and perform other operations, as will appear hereinafter.

Heretofore the various steps required to make paper cartons have been performed on 25 several separate and distinct machines, such for example, as a gluing machine for applying an adhesive to the paper strips, a tube winder for winding the strips into tubes, a tube cutter for cutting the tubes in proper 30 lengths, a bottom forming machine for making the end closures of the tube, and a spinning machine for securing said closures to the tube. But, by this invention the cost of these various operations is greatly 35 lessened, and the mechanism is preferably substantially of the shape and construction shown in the accompanying drawings.

The mechanism for placing end closures in the tubes after they are made is not specifically claimed herein, since it forms the 40 subject of my divisional application filed on the 24th day of January, 1912, No. 673,084, but it will be understood that the machine constituting the subject matter of said divisional case is operated from the same 45 source of power as is this machine. Further the mechanism claimed in this application including the revolving expansible mandrels and their coacting parts is especially designed for finishing the tubes, presenting them in the proper positions and firmly holding them in said positions while the mechanism claimed in said divisional application inserts end closures in the tubes 50 thus presented and held, and then crimps

the same securely in said tubes. After the bottoms are thus secured the mandrel mechanism which thus performs functions for both the tube forming and the tube closing mechanism, discharges the finished tubes. 60 In order, therefore, that the machine as an entirety, as well as its intimate relation with the tube closing mechanism may be fully understood, I have illustrated herein both the tube forming and the tube closing mechanisms. 65

Referring to said drawings forming a part of this specification in which like numerals designate like parts in all the views:—Figure 1 is a side elevational view 70 of the right hand side of the machine; Fig. 2 is a side elevational view of the left hand side of the machine; Fig. 3 is a front elevational view; Fig. 4 is a plan view of the carton forming end of the machine; Fig. 5 is a plan view of the printing and cutting mechanism; Fig. 6 is an enlarged detail 75 front view of the bottom forming and spinning mechanism; Fig. 7 is an enlarged horizontal sectional view of the forming punch 80 and die, and the paper feed; Fig. 8 is a sectional view taken on the line 8—8 of Fig. 7 and showing the bottom punched, formed, and inserted in the carton ready for spinning; Fig. 9 is a side elevational view of 85 one end of the machine showing the printing and cutting mechanism with the side frame removed for the sake of clearness; Fig. 10 is an enlarged side elevational view 90 similar to Fig. 9 but showing the parts in their relative position during the act of printing; Fig. 11 is a horizontal sectional view showing the type frame and guides; Fig. 12 is a cross sectional view taken on the line 12—12 of Fig. 11; Fig. 13 is a detail perspective view of the printing frame; Fig. 14 is a detail perspective view of one 95 of the type clamping slides; Fig. 15 is a side elevational view of the gluing and winding mechanism with the side frame removed, and also showing the winding roll drive and a mandrel in winding position; Fig. 16 is an end elevation of the parts shown in Fig. 15 looking from the left; Fig. 17 is a vertical cross sectional view 100 taken on the line 17—17 of Fig. 15; Fig. 18 is a horizontal cross sectional view taken on the line 18—18 of Fig. 15; Fig. 19 is a detail perspective view of one of the paper guiding fingers with its operating mecha- 110

nism; Fig. 20 is a detail perspective view of the carton ejecting mechanism and spinner driving cam; Fig. 21 is a detail view showing the carton being held by the safety latch in its ejected position; Fig. 22 is a detail view of the paper guiding racks showing the position they assume during the gluing operation; Fig. 23 is an enlarged detail view showing the mandrel incased in the winding and ejecting sleeve, and also showing the spinner; Fig. 24 is a horizontal cross sectional view of the parts shown in Fig. 23 with a carton and bottom inserted therein ready for spinning; Fig. 25 is an end view of the mandrel, and winding and ejecting sleeve, and showing the mandrel and forming plate removed; Fig. 26 is a cross sectional view taken on the line 26—26 of Fig. 24; Fig. 27 is a side elevational view of one of the wedge guides; Fig. 28 is an end elevational view of one of the wedge guides; Fig. 29 is a detail view of the spinner; Fig. 30 is a detail view of the mandrel and forming plate; Fig. 31 is a detail plan view of the mandrel expanding and contracting cams; Fig. 32 is a side elevational view of the parts shown in Fig. 31; Fig. 33 is a detail sectional view taken on the line 33—33 of Fig. 32; Fig. 34 is a diagrammatic view showing the working of the complete machine; Fig. 35 is a detail view showing a convolutely wound carton; Fig. 36 is a detail sectional view of a carton showing a bottom inserted therein; Fig. 37 is a detail sectional view of a carton showing a finished bottom formed thereon; and, Fig. 38 is a perspective view of a finished carton.

The general operation of this machine may be understood from the diagrammatic view shown in Fig. 34 in which paper from the roll 36 is first severed into suitable lengths to form a convolutely wound carton, while a suitable legend is printed by the means 47 on the paper before it is wound and in the right position for it to appear at the proper place on the outside of the finished article. The printed strips of paper are next supplied with glue and wound as at A into tubes, which are transferred to the point B, then to position C, then to position D, where a suitable mechanism punches out and forms bottom closures from the paper carried by roll 155, and inserts these closures in the ends of the tubes. The tubes with the closures in place, are next transferred to position E where the closures and tube are subjected to a spinning operation to firmly fix the closures in the tube, and the finished cartons are finally ejected from the machine at F. These various mechanisms will now be described in detail, and their relations one with the other will also be pointed out.

Referring first to Fig. 2, power may be supplied by any suitable means as by a belt

to the pulley 8, mounted on the shaft 7, carrying the pinion 6, meshing with the gear 5, mounted on the shaft 4, carrying the pinion 3, meshing with the gear 2, carried by the main power shaft 1, which latter distributes power to the various parts of the machine. The shaft 1 also carries the intermittent gear 9, meshing with the intermittent gear 10, mounted on the shaft 11, carrying the bevel gear 12, meshing with the bevel gear 13, carried by the shaft 14, which operates the press for forming the bottom closures, as will appear more fully below.

On the end of the shaft 1 opposite to that carrying the gear 2, is the gear 15, see Fig. 3. This gear meshes with the gear 16, and through the same operates a Geneva mechanism performing an operation and of a construction to be more fully described below, and said gear 16, through the shaft 17, operates a bevel gear 18, meshing with the bevel gear 19, carried by one end of the shaft 20.

The shaft 20 shown in Figs. 1 and 3 extends the entire length of the machine, and has on its other end the bevel gear 21, meshing with the bevel gear 22 mounted on the shaft 23, which latter shaft distributes power to the printing, cutting and paper feeding mechanism, as shown in Figs. 1 and 5, and now to be described. Mounted on said shaft 23 is the intermittent gear 24 meshing with the intermittent gear 25, mounted on the shaft 26, carrying the gear 27 meshing with the idler gear 30, driving the gear 28 on the shaft 31 and meshing with the gear 29 on the shaft 32. Carried by the shaft 31 is the paper feed roll 33, and carried by the shaft 32 is the feed roll 34, Figs. 5 and 9, while paper from the roll 36, carried by the bracket 37, is forced by said rolls into position to be cut into suitable lengths and to have a suitable legend printed thereon by mechanism, as will now appear. A screw tensioning means 35 for adjusting the feed roll 34 is provided, as shown in said figures; while the mechanism for cutting the strips of paper 36 into suitable lengths is operated by the intermittent gear 38, also mounted on the shaft 23, which drives the small intermittent gear 39 mounted on the stud 40 which likewise carries the gear 41 meshing with the gear 42, mounted on the outer end of shaft 43, see Figs. 1 and 5.

Carried on the inner end of the shaft 43 is a disk 44 which is provided with a crank pin 45. This crank pin, Figs. 5, 9 and 10, through the connecting rod 46 reciprocates the printing frame 47. The said printing frame 47 is preferably of the shape and construction shown in Figs. 9, 10, 11, 12 and 13, and slides to and from the paper 36 between the guides 48, which are mounted on the cross frame 49 held to the sides of the machine.

Secured to the under side of the printing frame 47 and held thereto by four equalizing studs 50, and by clamping slides 51, Fig. 14, is the electrotype holder 52. These equalizing studs 50, mounted within the sliding printing frame 47 are provided on their lower ends with reduced portions 53 and with heads 54, and at their upper ends with the adjusting nuts 55. The electrotype holder 52 has mounted on its under side the electrotype 56 and also accommodates therein the said slides 51. When it is desired to remove or change the electrotype holder, it is only necessary to pull out the slides 51 until the enlarged holes 57, at the end of the slots 58, register with the heads 54 of the equalizing studs 50. Likewise, carried by the shaft 23 and opposite the driving gears is a cam 59 for driving the inking mechanism associated with the printing frame 47, which will now be described, see Figs. 5, 9, and 10.

The cam 59 oscillates the lever 60 mounted on the shaft 61, which is supported by the bearings 63, Fig. 5, on the side frame of the machine. This shaft also has mounted thereon the pair of operating levers 62. The outer ends of these levers 62 are slotted to engage the rollers 630, mounted on the ink roll levers 64, Figs. 5, 9 and 10. These latter levers are mounted on the studs 65 in the sides of the machine and carry in slots 66 the ink rolls 67, see Figs. 9 and 10. Springs 68 mounted on the ink roll levers 64 hold the ink rolls, when in different positions, respectively against the type 56 and ink plate 74.

Extending down from the cross frame 49 is a web 69, Fig. 10, to which is pivotally mounted as at 70 a rocking lever 71 carrying a spring pressed pawl 72 which contacts with a ratchet 73 on the revolving inking plate or disk 74 which is pivotally mounted on the cross frame 49 as at 740. This spring pressed pawl is for operating the revolving ink disk 74 when the rocking lever 71 is engaged at its outer end by the pin 75 mounted on the ink roll lever 64, and while said pin is performing its downward stroke, Figs. 5, 9, and 10.

The rocking lever 71 is returned, see Fig. 10, by a spring 76 until it comes into contact with the stop pin 77 mounted on said web 69, rigid with the cross frame 49, and thereby reengages the ratchet 73 of the plate 74.

In order that the strips of paper 36 to be printed upon by the mechanism just described, may be automatically cut into suitable lengths, as they are unwound from the roll, the following mechanism is provided:—The disk 44 in addition to carrying the crank pin 45, is provided with the cam slot 78 in which operates a roller 79 mounted on one end of the bell crank lever 80

which lever rocks on the stud 81, mounted in a bearing 82 on the cross frame 49. Running in a slot 83, on the opposite or forked end 84 of the bell crank lever, see Figs. 5, 9 and 10, are studs 85 which are mounted in the upper end of the cutting frame 86. At the lower end of this cutting frame 86 is held the knife blade 87 for shearing the paper 36 against the lower knife blade 88 on the frame of the machine, see Figs. 9 and 10. Said cutting frames 86 travel to and from the paper between the cross frame 49 and the guide bars 89 mounted on the side of the machine, and the parts are so timed that the shearing of the paper takes place immediately following the type impression. The feeding of the paper by means of the rolls 33 and 34 is also so adjusted and timed that a length just sufficient when wound to form the desired tube is severed at each operation. Further, the printing frame is so located relatively to the paper that the portion of the severed strip which will later form the outside of the finished tube, receives the printed impression.

Immediately after the type leaves the paper, the gluing and winding mechanism, now to be described, is brought into operation.

Carried by the shaft 20 which, as above stated, runs the entire length of the machine, are two cams 90 and 91, Figs. 1, 15 and 16, and these cams operate respectively the gluing and winding rolls 92 and 93. The operating mechanism of these two rolls is the same, except the winding cam 91, Fig. 16, has a longer dwell, as will be more fully hereinafter disclosed.

94 and 95 indicate cam following levers for the gluing and winding mechanisms pivotally mounted on brackets 96 and 97 held to the frame of the machine, Figs. 15 and 16. These levers have pivotally mounted on their inner end bearings 98 and 99, Figs. 15 and 16, yoke bars 100 and 101 which yoke bars carry at their outer ends connecting rods 102 and 103. These connecting rods are pivotally connected at their upper ends to the toggles 104 and 105. Each of the toggles 104 and 105, are pivotally connected at one end to the side frame of the machine by a stud 106, and are also pivotally mounted on the shafts 107 and 108 of the gluing and winding rolls 92 and 93, respectively. These shafts also operate in slots 109 in the side frames of the machine, see Figs. 1 and 15.

It will be clear from the foregoing that through the operation of the cam following levers 94 and 95 on the cams, the rolls 92 and 93 through the toggles and connecting rods are brought to the dotted or operating position shown in Fig. 15. The return movement of these rolls and their connect-

ing parts is brought about by the springs 111 and 112 connected to the cam following levers 94 and 95 and the frame of the machine, as shown.

5. When the gluing roll 92 is moved forwardly and downwardly into its dotted line operative position, it causes the paper to be pressed against the glue covered surface of the roll 113 mounted on a shaft within the glue pot 114. This roll 113 is revolved by its frictional contact with the paper as it is moved by the rolls, and the glue is evenly distributed on the under side of the said paper as long as roll 92 is in its operative 10 position. The rotating movement of the roll 113 keeps its surface covered with a thin film of glue the thickness of which is controlled by the knife edge 115 mounted on the glue pot 114.
15. The paper guide 116, Figs. 15, 16, 17, 18 and 19, for keeping the paper in proper alinement after it leaves the feed rolls 33 and 34, has pivotally mounted on its under side and directly beneath the gluing roll 92, 20 a pair of guide fingers 117, which fingers are for the purpose of guiding and supporting the paper between the rolls 92 and 113 where it would be otherwise unsupported when the gluing roll 92 is in its upper or 25 idle position. This paper guide 116 is also provided with elongated openings 1160, see Fig. 18, through which the enlarged sections of the gluing roll 92 are adapted to pass. These guide fingers 117 are pivotally connected as at 118 through the rod 119 and 30 lever 120, to the connecting rod 102, which operates the gluing roll 92. They are accordingly operated by said rod to lift the paper when the gluing roll is returning to 35 its idle position. The fingers 117 also serve, when in the position indicated in Fig. 15, to guide a fresh portion of the paper above the glued surface of the roll 113.

40. The means for supporting the paper between the gluing and winding positions will now be described. This means comprises a series of stationary bars 121, movable bars 122 and connected parts for taking care of both the clean and glued parts of the paper 45 during travel through the paper guide 116 to the winding roll and mandrel, see Figs. 1, 15, 17, 18 and 22. The stationary bars 121 are rigidly held on shafts 123 mounted in the side frames of the machine. The movable bars 122 are supported on shafts 1220 which are in turn pivotally mounted by links 124 at 125 to the side frames of the machine. One of the shafts 1220 is extended, at each side, beyond the frame of the machine and 50 is engaged by the slots 126 in the levers 127 at their upper ends. These levers 127 are mounted on the shaft 128 which is supported in the side frames of the machine and are operated through the lever 130 by the cam 55 129, which cam is mounted on the power

distributing shaft 20, see Figs. 1, 15, 16 and 22.

The parts are so timed that only a portion of the paper strip is depressed by the roll 92 into contact with the gluing roll 113, and therefore, said strip is provided with clean and glued portions, as above indicated.

In the operation of the machine and immediately before the period of gluing, the cam 129 through the levers 130 and 127 70 causes the movable bars 122 to drop below the stationary bars 121 and from the full line positions shown in Figs. 15 and 17, to the dotted line position shown in Fig. 22, thus the movable bars 122 which supported 80 the clean or unglued parts of the paper, are now held below the stationary bars 121 and kept free from glue while the glued portion of the paper travels along the stationary bars 121 after it has left the glue covered 85 roll 113. The upper edges of these stationary bars are sharpened to prevent them from holding any material quantity of the glue after the glued end of the paper has left the stationary bars. The timing of the parts is 90 also such that when a clean portion of the paper has reached the gluing rolls, the movable bars are returned to their upper position through the cam 129 and its driving mechanism.

95. So far as has now been disclosed, it will be clear from the foregoing that paper is fed from the roll 36 by the feed rolls 33 and 34 through the guide 116 up to the point X into contact with the mandrel 138 before any 100 glue is applied thereto. It further receives a suitable impression from the printing mechanism 47, whereupon a suitable length of paper for making the required tube is then severed by the knife 87. At the same 105 time, that portion of the paper strip beneath the roll 92, is brought into contact with the glue roll 113, and receives a sufficient quantity of glue, when said glued portion is passed on to the winding rolls 93 and 138 to 110 be wound in a tube.

115. The mechanism for winding the glue coated strip into a tube and for putting a bottom into the same, will now be more fully disclosed.

120. Mounted at the right hand side of the machine on the end of the shaft 17, Fig. 3, the drive of which through the gear 16, has been previously described, is the Geneva mechanism already referred to. This mechanism 120 comprises a crank 132, Fig. 1, carrying on its outer end a roller 133, which roller contacts intermittently with the Geneva wheel 134 mounted on the shaft 135. Mounted also on the shaft 17 is the locking disk 136, Figs. 1 and 3, for locking intermittently the Geneva wheel. This mechanism is mounted in a suitable bracket 1360, Figs. 3 and 4, in the frame of the machine. The shaft 135 also has rigidly mounted thereon a spider 130

137 for supporting and carrying six mandrels 138, Figs. 1, 3 and 4, arranged sixty degrees apart. These mandrels are expandible, Figs. 23, 24, 25 and 26, and are 5 exactly the same in detail, construction and operation as those previously described in my former application Serial No. 564,602; filed June 2, 1910; and entitled Crimping machine for cartons.

10 Mounted on each side of the expanding mandrels 138 and securely bolted to the spider 137, Figs. 3, 4, 23 and 24 are two guide rods 139 which guide rods are for the purpose of supporting a sliding frame 140, 15 which frame comprises a winding sleeve 141 and ejecting collar 142, Figs. 3, 25 and 26.

143 indicates a forming disk, see Figs. 24 and 30, securely held to the outer wedge guide of the mandrel, the purpose of which 20 will be hereinafter described.

Considering now one of the mandrels being held by the Geneva mechanism in its winding position, as shown in Figs. 1, 3, 4 and 15, it will be seen that the toggle mechanism 105, Fig. 15, will force the roll 93 forward and downwardly into its dotted line operative or paper feeding position, and will therefore, when rotated in the manner to be described, cause, in connection with a mandrel 138, the glued strip of paper to be fed forward between the outer surface of the said mandrel 138 and the inner surface of the surrounding sleeve 141.

Each of the mandrels is further provided 35 with a gear 144, Figs. 1, 3 and 4, which, as the spider revolves, contacts with the friction roll of yielding material 146, Figs. 4 and 16, rigid with the winding roll 93, and is revolved for the purpose of winding the 40 paper. This winding roll carrying the friction roller gear 146 is driven by the sprocket wheel 147 mounted on the winding roll shaft 108 through the chain 148 by the sprocket wheel 149, which sprocket together with the 45 bevel gear 150, is mounted on the stud 151. The bevel gear 150 is driven by bevel gear 152 mounted on the power distributing shaft 20. Therefore, when the paper has been fed to the point X, Figs. 15 and 22, the winding 50 roll 93 being brought to its winding position previously described will through its rotary motion, force the paper and cause it to be guided around the mandrel within sleeve 141. To aid in this operation, the 55 sleeve 141 is provided with an opening 153 to permit the winding roll to contact with the mandrel, see Fig. 15.

To prevent the paper from taking an improper path in its winding position, two 60 lips 154, Fig. 20, are provided on the sleeve 141, which lips extend within the recesses 930 on the winding roll 93.

It will now be clear from the foregoing, 65 that as the mandrels 138 are brought into the position A, Fig. 1, the winding roll 93

will be moved down into its dotted line position, Fig. 15, into contact with the glue coated paper and said mandrel, while the friction roll 146 will contact with the gear 144 and rotate said mandrel on its axis, and thereby wind up said glued paper strip into 70 a tube.

The tube being formed the Geneva mechanism will move the mandrel and tube to the position B where it may be subjected to 75 heat for the purpose of drying and setting the adhesive, which heat may be supplied by a blast of hot air or by gas burners, as in my said application above, and if desired, this drying may be continued at the position C, which the mandrel next assumes, as it is intermittently revolved by the spider 80 under the influence of the Geneva wheel. The carton and mandrel is next brought to the position D, Fig. 1, where the bottom is 85 formed and inserted into the tube, as will now be described.

The mechanism for forming the bottom is situated in suitable framework on the left hand side of the machine, and comprises the 90 feeding mechanism for the paper out of which the bottom is formed, and the blanking and bottom forming mechanism.

155 indicates the bottom paper roll, Fig. 2, supported on the bracket 156, the paper 95 from which is fed through paper guide 157, Fig. 7, by the feed rolls 158 and 159, which rolls are operated intermittently through suitable spur gears 160, 161 and 162, and bevel gears 163 and 164, which bevel gear 164 is mounted on the mandrel spider shaft 135, see Figs. 1, 2, 4 and 7. A screw tensioning means 165 for adjusting the feed roll 158 is provided, as shown in Fig. 7.

The bottom blanking and forming mechanism comprises the blanking punch 166, 100 Figs. 6, 7 and 8, operated through connecting rods 167 by eccentrics 168 and the forming punch 169 operated through the connecting rod 170 by the crank 171. The eccentrics 168 are integral with the vertical shaft 14, Fig. 2, previously mentioned, and are so arranged that the blanking punch 166 cuts out blanks in the form of paper disks at the cutting edge 172 of the blanking die 173, see 115 Figs. 7 and 8. The crank 171 is also integral with and so arranged on the vertical shaft 14 that the forming punch 169 follows within the blanking punch carrying the paper disk on through the forming die 174 120 and into the carton, as shown in Fig. 8.

The connecting rod 170 is adjustable, as shown, for regulating the movement of the forming punch and a means is also provided for regulating the time of the blanking, consisting of the nut 175, which lengthens or shortens the operation of the blanking punch 166. When the proper adjustment of the blanking punch is obtained, it is held in a locked position by the bolt 176. The blank- 125 130

ing punch frame slides within the guides 177 in the framework of the machine.

From the mechanism so far disclosed, it will be clear that the paper strips 36 which 5 were automatically cut into suitable lengths, subjected to a printing operation, furnished with an adhesive, rolled into a tube, and subjected to a drying operation, are brought opposite the bottom forming means at the 10 point D, and there a flanged cup shaped disk 1430, Figs. 24 and 36, forced into said formed tube. The Geneva wheel next moves the mandrel and tube with its closure in place to the position E, Fig. 1, at 15 which point the flange of the disk closure and the edge of the tube are subjected to a spinning operation for the purpose of firmly and tightly securing the closure in place, as will now be disclosed.

20 Mounted on the stud 178 is a small spur gear 179 which meshes with and is driven by the spur gear 5, Figs. 2 and 4.

180 indicates a bevel gear also mounted on the stud 178 which meshes with a bevel gear 25 181 on the lower end of the diagonal shaft 182. This shaft has mounted on its upper end a bevel gear 183 which meshes with and drives the bevel gear 184 on the outer end of the shaft 185. Mounted on the inner end 30 of this shaft 185 is a spur gear 186 which meshes with a spur gear 187 mounted on the outer end of the idler shaft 188. On the inner end of this idler shaft is a spur gear 189 which meshes with a wide spur gear 190 35 mounted on the inner end of the spinner shaft 191 directly behind the spinner disk 192, see Figs. 3, 4, 6 and 29. This spinner shaft is slidably mounted within the frame of the machine and its outer or cam follower end is held against a cam 193 on the shaft 14, by the spring 194. The spinner disk 192 is projected forward into contact with the tube and closure through the cam 193 at its proper time for spinning.

40 45 The details of the spinning mechanism are not disclosed herein, but they will be clear from my prior application above. Suffice it to say, the disk 192 is preferably provided with perforations 1920, Fig. 29, which 50 serve to roughen or break down the edges of the tube and closure, and when it rotates, it is forced longitudinally of its shaft and the tube so that the said edges are curled inward and spun together in such a manner as 55 to make an exceedingly strong and liquid tight joint, Fig. 37.

The carton being finished, it moves to the 60 position F, Fig. 1, where it is automatically ejected from the machine by the means now to be disclosed, especial reference being had to Figs. 1, 2, 3 and 4. In this position the notched ejector slide 195, traveling on the rod 196, supported on the frame of the machine, engages the ejecting collar 142, 65 see Figs. 3, 4, 20 and 21. Through the

connecting rod 197 pivotally connected to the crank 198 mounted on the end of the vertical press shaft 14 the ejector slide moves along the rod 196 and carries the carton off the mandrel into the receptacle 199. When 70 the carton has entered the receptacle 199, it is held by the finger 200 from following the ejector slide back on the mandrel during its return stroke, see Fig. 21. The lever 201 which carries on its inner end the finger 200 75 is pivotally mounted at 202 to the side of the receptacle 199 and is operated by the cam 203 on the rotating press shaft 14. After a finished carton is delivered into the receptacle 199, the succeeding one forces out its predecessor, and the said cartons thereafter may be caught in any suitable receiver, not shown.

In the foregoing description the tubes are tightly wound around the mandrels and they must be firmly held thereon during the 80 crimping operation. On the other hand, they must be capable of easy stripping from the mandrels when they are finished. To aid in the stripping operation, the mandrels are made of an expanding and contracting type, 85 as will be clear from Figs. 24, 25 and 26, their construction being practically the same as those disclosed in my prior application above, and they are expanded during the 90 making of the carton and contracted after 95 the crimping operation by means of mechanism substantially the same as that disclosed in said prior application. That is to say, during the rotation of the spider 137 the expansion and contraction of the mandrels 100 is accomplished by the expanding cam 204 and contracting cam 205 supported on the stationary wheel 206, see Figs. 3, 4, 31 and 32. These cams are rigid with the wheel 206, and the latter is mounted on the frame 105 of the machine. The mandrel shaft α carrying the mandrel in traveling from the spinning position E to the ejecting position F follows along the path of cam 205, is moved longitudinally permitting its cams 110 to disengage its wedge expanding members comprising the wedges 330 and holders 331, Figs. 24, 27 and 28, and thereby allows the springs 332 to contract the mandrel, all as is disclosed in said prior application. In 115 traveling from the ejecting position F back to the winding position A, the mandrel shaft α follows along the cam 204 thereby partly expanding the mandrel again just before the tube is formed. In traveling from the 120 position A to the idle or drying position B, the shaft α continues to follow the cam 204 when the mandrel becomes completely expanded and stays expanded through the further idle or drying positions C, punching 125 and forming position D, and spinning position E. A spring actuated segment 207 is mounted on the stationary wheel 206 opposite the spinning position, in order to render the operation more smooth and certain. 130

The operation of the machine will be clear from the foregoing, but may be briefly summarized as follows:—Paper for forming the body of a carton is fed from the paper roll 36 by the feed rolls 33 and 34 through the paper guide 116 until it reaches the winding position A. Through intermittent gears 24 and 25, and other mechanism, the paper feed is so timed that it reaches the said position A immediately after one of the mandrels reaches the same point. Through intermittent gears 38 and 39 the printing mechanism is caused to imprint a legend on the paper immediately after it comes to a stop and at a point which will make it appear in the desired position on the outside of the finished carton 300, Fig. 38. As soon as the electrotype leaves the paper, the knife 87 through the cam disk 44 and its operating mechanism cuts the paper into a predetermined length which (see Fig. 34) is sufficient to convolutedly wind the carton 300 to a desired thickness, see Fig. 35. After the movement of the knife 87, the cam 59 and its connecting mechanism causes the ink rolls 67 to travel over the ink plate 74, Fig. 10, thereby taking up ink, and later the said ink rolls 67 are carried to the electrotype and caused to spread ink thereover, Fig. 9. Simultaneously with the operation of printing and cutting, the roll 92 and winding roll 93 are brought into their operative positions to spread an adhesive on and to wind the strip, as has been previously described. The friction gear 146 on the shaft 108 revolving through its chain drive from the shaft 20 engages the gear 144 on a mandrel and rotates the latter a sufficient amount to wind the glued strip into a tube. The degree of rotation is governed by the lifting portion of the cam 91, see Fig. 16. The roll 93 also mounted on the shaft 108, in revolving pulls the paper from the glue roll 113 thus spreading the glue on all of the paper except the first complete turn, which in length is equal to a complete circumference of the carton to be made. The paper is chosen of a length such that when wound over the mandrel, a sufficient number of revolutions, the walls of the carton will have the required thickness. To prevent glue from getting on that part of the paper which is not to be glued and thus gumming up the mandrel, the movable bars 122 support the unglued portion and the stationary bars 121 support the glued portion of said paper. After the carton has been wound on the partially expanded mandrel in the position A, it is then brought by means of the Geneva wheel 134, to one drying position B, during which travel the said mandrel is expanded to its utmost, thereby holding the finished tube under pressure between the mandrel 138 and the sleeve 141. The mandrel containing the

carton is then brought to a second drying position C by the Geneva wheel, and then to the bottom forming and punching position D, where the bottom from the paper roll 155 is blanked, formed and inserted into the tube. After leaving this position, it is then brought to the spinning position E where the bottom is firmly secured to the tube and preferably given by means of the member 143, Fig. 24, the form shown in Fig. 37. The mandrel in passing from spinning position E to the ejecting position F is contracted by means of the cam 205, thus allowing the carton to be readily forced off the mandrel by the ejector means 142 and 195, Fig. 20. The Geneva mechanism causes all the mandrels to be brought to their various operating positions successively and to be locked in place while the operations are being performed.

It will be observed from the foregoing that the operation of the machine is such as to never lose control of the paper at any stage whatever. The paper starts into the machine under the firm control of the feeding rolls, it is forced into and out of contact with the glue applying roll, it is forced into the grip of the winding mandrel; the latter expands and grips the tube firmly while the bottom is being applied, it is forced off the mandrel, and is forcibly prevented from returning. The result is a machine, nothing being left to chance, in which every operation goes on with great rapidity and certainty.

It is obvious that those skilled in the art may vary the details of construction as well as the arrangement of parts without departing from the spirit of my invention, and therefore I do not wish to be limited to such features, except as may be required by the claims.

What I claim is:—

1. In a machine for making paper cartons, the combination of a paper feeding means; means to cut the paper into suitable lengths; a slotted guide for said paper; supports for said paper in said guide; means extending longitudinally of said guide to lift said paper from said supports at predetermined intervals; means to apply an adhesive to said paper; and means to wind said cut paper into a tube, substantially as described.

2. In a machine for making paper cartons, the combination of a paper feeding means comprising a plurality of rolls between which said paper passes; a slotted guide for said paper; supports for said paper in said guide; means extending longitudinally of said guide to lift said paper from said supports at predetermined intervals; means to cut the paper into suitable lengths; means to apply an adhesive to said paper through said slotted guide; and

means to wind said cut paper into a tube, substantially as described.

3. In a machine for making paper cartons, the combination of a paper feeding means; a slotted guide for said paper; supports for said paper in said guide; means extending longitudinally of said guide to lift said paper from said supports at predetermined intervals; means to cut the paper into suitable lengths comprising a reciprocating knife; means to apply an adhesive through said slotted guide to said paper; and means to wind said cut paper into a tube, substantially as described.

15 4. In a machine for making paper cartons, the combination of a paper feeding means comprising a plurality of rolls between which said paper passes; a slotted guide for said paper; supports for said paper in said guide; means extending longitudinally of said guide to lift said paper from said supports at predetermined intervals; means to cut the paper into suitable lengths comprising a reciprocating knife; 20 means comprising a roller adapted to extend through the slot in said guide to apply an adhesive to said paper; and means to wind said cut paper into a tube, substantially as described.

25 5. In a machine for making paper cartons, the combination of a paper feeding means; a slotted guide for said paper; supports for said paper in said guide; means extending longitudinally of said guide to lift said paper from said supports at predetermined intervals; means to cut the paper into suitable lengths; means to apply an adhesive to said paper comprising a roll carrying said adhesive, and a movable roll 30 adapted to move through said slotted guide toward and from said adhesive carrying roll; and means to wind said cut paper into a tube, substantially as described.

35 6. In a machine for making paper cartons, the combination of a paper feeding means comprising a plurality of rolls between which said paper passes; a slotted guide for said paper; supports for said paper in said guide; means extending longitudinally of said guide to lift said paper from said supports at predetermined intervals; means to cut the paper into suitable lengths comprising a reciprocating knife; means to apply an adhesive to said paper comprising a roll carrying said adhesive; a movable roll adapted to move through said slotted guide toward and from said adhesive carrying roll; and means to wind said cut paper into a tube, substantially as 40 described.

45 7. In a machine for making paper cartons, the combination of a paper feeding means; a slotted guide for said paper; supports for said paper in said guide; means extending longitudinally of said guide to

lift said paper from said supports at predetermined intervals; means to automatically cut the paper into predetermined lengths; an adhesive applying means comprising a roller; and means comprising a reciprocating roller adapted to pass through the slots in said guide to force said paper into contact with said adhesive applying means at predetermined intervals, substantially as described.

75 8. In a machine for making paper cartons, the combination of a paper feeding means; means to automatically cut the paper into predetermined lengths; an adhesive applying means; means to normally hold the paper out of contact with said adhesive applying means comprising pivoted fingers; and means to force said paper into contact with said adhesive applying means at predetermined intervals, substantially as 80 described.

90 9. In a machine for making paper cartons, the combination of a paper feeding means; means to automatically cut the paper into predetermined lengths; an adhesive applying means comprising a roll and an adhesive container in which said roll dips; means to normally hold the paper out of contact with said adhesive applying means comprising pivoted fingers; and means to force said 95 paper into contact with said adhesive applying means at predetermined intervals, substantially as described.

95 10. In a machine for making paper cartons, the combination of a paper feeding means; means to automatically cut the paper into predetermined lengths; an apertured guide for said paper; an adhesive applying means comprising a roll and an adhesive container in which said roll dips; 100 means to normally hold the paper out of contact with said adhesive applying means comprising pivoted fingers; and means to force said paper into contact with said adhesive applying means at predetermined intervals, substantially as described.

105 11. In a machine for making paper cartons, the combination of a paper feeding means; a paper guiding means; an adhesive applying means; pivoted fingers for normally holding the paper out of contact with said adhesive applying means; and a movable roll adapted to force said paper into contact with said adhesive applying means at predetermined intervals, substantially as 110 described.

115 12. In a machine for making paper cartons, the combination of a paper feeding means; a perforated paper guiding means; an adhesive applying means; pivoted fingers located opposite the perforations in said guiding means for normally holding the paper out of contact with said adhesive applying means; and a movable roll adapted to enter said perforations and force said 120 125 paper into contact with said adhesive applying means; and a movable roll adapted to enter said perforations and force said 130

- paper into contact with said adhesive applying means at predetermined intervals, substantially as described.
13. In a machine for making paper cartons, the combination of a paper feeding means; a paper guiding means; an adhesive applying means; pivoted fingers for normally holding the paper out of contact with said adhesive applying means; a movable roll adapted to force said paper into contact with said adhesive applying means at predetermined intervals; and cam and lever connections for operating said movable roll, substantially as described.
14. In a machine for making paper cartons, the combination of a paper feeding means; automatic means for cutting the paper into suitable lengths; means for winding the paper into a tube; a paper guiding means; an adhesive applying means; pivoted fingers for normally holding the paper out of contact with said adhesive applying means; and a movable roll adapted to force said paper into contact with said adhesive applying means at predetermined intervals, substantially as described.
15. In a paper tube making machine, the combination of means for cutting the paper into suitable lengths; a glue applying means; a slotted guide through which said paper passes; means disposed longitudinally of said guide for periodically raising said paper in said guide; additional means in said guide for supporting said paper when not raised by said last mentioned means; a roll for forcing the paper into contact with said glue applying means; a winding means; a roll for forcing said paper into contact with said winding means; and means for bodily moving said rolls at predetermined intervals, substantially as described.
16. In a paper tube making machine, the combination of means for cutting the paper into suitable lengths; a glue applying means; a slotted guide through which said paper passes; means disposed longitudinally of said guide for periodically raising said paper in said guide; additional means in said guide for supporting said paper when not raised by said last mentioned means; a roll for forcing the paper into contact with said glue applying means; a winding means; a roll for forcing said paper into contact with said winding means; and means comprising cams and levers for bodily moving said rolls at predetermined intervals, substantially as described.
17. In a paper tube making machine, the combination of means for cutting the paper into suitable lengths; a glue applying means; a slotted guide through which said paper passes; means disposed longitudinally of said guide for periodically raising said paper in said guide; additional means in said guide for supporting said paper when
- not raised by said last mentioned means; a roll passing through a slot of said guide for forcing the paper into contact with said glue applying means; a winding means; a roll for forcing said paper into contact with said winding means; and means comprising cams and levers for bodily moving said rolls at predetermined intervals, substantially as described.
18. In a paper tube making machine, the combination of means for cutting the paper into suitable lengths; a glue applying means; means comprising fingers for normally holding said paper out of contact with said glue applying means; a roll for forcing the paper into contact with said glue applying means; a slotted guide for said paper through which said last mentioned roll passes; a winding means; a roll for forcing said paper into contact with said winding means; a movable support for said paper disposed longitudinally of said guide; and means comprising cams and levers for bodily moving said rolls at predetermined intervals, substantially as described.
19. In a paper tube making machine, the combination of means for cutting the paper into suitable lengths; a glue applying means; pivoted fingers for normally holding said paper out of contact with said glue applying means; a roll for forcing the paper into contact with said glue applying means; means for automatically cutting said paper into suitable lengths; a guide provided with longitudinally disposed supports for said paper; a winding means; a roll for forcing said paper into contact with said winding means; and means for bodily moving said rolls at predetermined intervals, substantially as described.
20. In a paper tube machine, the combination of a slotted paper guide; movable supports for the paper in said guide; a glue applying roll; a movable roll adapted to pass through said guide and to contact with said glue applying roll; a tube winding means; a movable roll adapted to contact with said winding means; and connections adapted to bodily move at predetermined intervals said movable rolls into contact respectively with said glue applying and said winding means, substantially as described.
21. In a paper tube machine, the combination of a paper guide; a glue applying roll; a movable roll adapted to contact with said glue applying roll; a tube winding means; a movable roll adapted to contact with said winding means; stationary means in and disposed longitudinally of said guide for supporting the glue coated paper; longitudinally disposed means for holding said paper out of contact with said stationary means; and connections adapted to bodily move at predetermined intervals said movable rolls into contact respectively with said

- glue applying and said winding means, substantially as described.
22. In a paper tube machine, the combination of a paper guide; a glue applying roll; a movable roll adapted to contact with said glue applying roll; a tube winding means; a movable roll adapted to contact with said winding means; movable means in said guide for supporting the paper before glue has been applied thereto; stationary means in said guide for supporting the glue coated paper; and connections adapted to bodily move at predetermined intervals said movable rolls into contact respectively with said glue applying and said winding means, substantially as described. 70
23. In a paper tube machine, the combination of a severing means; a gluing means; a guiding means; a stationary means in said guiding means for supporting the glued portions of the paper; and a movable means in said guiding means for supporting the unglued portions of the paper, substantially as described. 75
24. In a paper tube machine, the combination of a severing means; a gluing means; means to normally support the paper above the gluing means; a guiding means; a stationary means in said guiding means for supporting the glued portions of the paper; and a movable means in said guiding means for supporting the unglued portions of the paper, substantially as described. 80
25. In a paper tube machine, the combination of a severing means; a gluing means; pivoted fingers adapted to normally support the paper above said gluing means; a guiding means; a stationary means comprising knife edge supports in said guiding means for supporting the glued portions of the paper; a movable means in said guiding means for supporting the unglued portions of the paper; and cam and lever connections for lowering said movable means below said stationary means at predetermined intervals, substantially as described. 85
26. In a paper tube machine, the combination of a paper feeding means; means to print upon the paper at predetermined intervals; a severing means; a gluing means; a guiding means; a stationary means in said guiding means for supporting the glued portions of the paper; and a movable means in said guiding means for supporting the unglued portions of the paper, substantially as described. 90
27. In a machine for making paper cartons, the combination of a pair of feed rolls for the paper; a glue applying roll; means to hold the paper normally out of contact with said glue applying roll; a movable roll adapted to force the paper into contact with the glue applying roll; a printing mechanism adapted to imprint at predetermined intervals a legend on said paper; a severing mechanism adapted to cut the paper into predetermined lengths; a guide for the paper; supports in said guide; a winding mechanism adapted to form a tube from the severed paper; and a movable roll adapted to aid in forcing the paper around the winding mechanism, substantially as described. 95
28. In a paper tube machine, the combination of means for feeding, cutting and gluing paper strips; a mandrel for receiving said strips; a movable roll adapted to force said strips into contact with said mandrel; a shell surrounding said mandrel; and means rigid with said roll for rotating said mandrel to form a tube from said strips, substantially as described. 100
29. In a paper tube machine, the combination of means for feeding, cutting and gluing paper strips; a mandrel for receiving said strips; a movable roll provided with grooves adapted to force said strips into contact with said mandrel; means for bodily moving said roll; a shell having guiding fingers adapted to enter said grooves surrounding said mandrel; and means for rotating said mandrel to form a tube from said strips, substantially as described. 105
30. In a paper tube machine, the combination of a plurality of mandrels each provided with an inclosing shell; means for revolving said mandrels at predetermined intervals along a circular path; means for stopping and locking said mandrels in predetermined positions in said path; means for feeding, cutting and gluing strips of paper and forcing them successively to said mandrels; and means rigid with said forcing means for correspondingly causing said mandrels to wind said paper into tubes, substantially as described. 110
31. In a machine for making paper cartons, the combination of a paper feeding means; an adhesive applying means; pivoted fingers to support and normally hold the paper out of contact with said adhesive applying means; a slotted guide through which the paper passes after having contacted with said adhesive applying means; supports extending longitudinally of said guide adapted to contact with the glue coated paper; and means adapted to pass at predetermined intervals through the slots of said guide to cause said paper to contact with said adhesive applying means, substantially as described. 115
32. In a machine for making paper cartons, the combination of a paper feeding means; an adhesive applying means; pivoted fingers to normally hold the paper out of contact with said adhesive applying means; a slotted guide through which the paper passes after having contacted with said adhesive applying means; supports disposed longitudinally of said guide adapted to contact with the glue coated paper; means 120
- 60 to hold the paper normally out of contact with said glue applying roll; a movable roll adapted to force the paper into contact with the glue applying roll; a printing mechanism adapted to imprint at predetermined intervals a legend on said paper; a severing 125
- 65 mechanism adapted to cut the paper into predetermined lengths; a guide for the paper; supports in said guide; a winding mechanism adapted to form a tube from the severed paper; and a movable roll adapted to aid in forcing the paper around the winding mechanism, substantially as described. 130

adapted to pass at predetermined intervals through the slots of said guide to cause said paper to contact with said adhesive applying means; a reciprocating connection for actuating said last named means; and means joined to said connection for controlling said pivoted fingers, substantially as described.

33. In a machine for making paper cartons, the combination of a paper feeding means; an adhesive applying means; pivoted fingers to normally hold the paper out of contact with said adhesive applying means; a slotted guide through which the paper passes after having contacted with said adhesive applying means; supports disposed longitudinally of said guide adapted to contact with the glue coated paper; independent, movable, supports also disposed longitudinally of said guide adapted to lift at intervals the paper from said first named supports; and means adapted to pass at predetermined intervals through the slots of said guide to cause said paper to contact with said adhesive applying means, substantially as described.

34. In a machine for making paper cartons, the combination of a paper feeding means; an adhesive applying means; pivoted fingers to normally hold the paper out of contact with said adhesive applying means; a slotted guide through which the paper passes after having contacted with said adhesive applying means; supports disposed longitudinally of said guide adapted to contact with the glue coated paper; independent movable supports also disposed longitudinally of said guide adapted to lift at intervals the paper from said first named supports; means adapted to pass at predetermined intervals through the slots of said guide to cause said paper to contact with said adhesive applying means; a reciprocating connection for actuating said last named means; and means joined to said connections for controlling said pivoted fingers, substantially as described.

35. In a machine for making paper cartons, the combination of a paper feeding means comprising a pair of rollers; an adhesive applying means comprising a glue pot and a roller therein; pivoted fingers to normally hold the paper out of contact with said adhesive applying means; a reciprocating rod; links connecting said fingers and rod; a slotted guide through which the paper passes after having contacted with said adhesive applying means; supports disposed longitudinally of said guide adapted to contact with the glue coated paper; independent, movable supports also disposed longitudinally of said guide adapted to lift the paper at intervals from said first mentioned supports; means comprising a roller adapted to pass at predetermined intervals through

the slots of said guide to cause said paper to contact with said adhesive applying means; connections between said last named means and said reciprocating rod; a rotating cam; and connections between said cam and rod for reciprocating the latter, substantially as described.

36. In a machine for making paper cartons, the combination of a power distributing shaft; a second shaft; gear connections between said first and second mentioned shafts; a paper feeding means; gear connections between said second shaft and said paper feeding means; a third shaft; connections between said second and third shafts; a printing means; connections between said third shaft and said printing means for operating the latter; a severing means; connections by which said severing means are operated by the connections associated with said printing means, means associated with said severing means for guiding the paper; and means associated with said guiding means for rolling the guided paper into a tube; substantially as described.

37. In a machine for making paper cartons, the combination of a power distributing shaft; a second shaft; connections between said first and second shafts; a disk on said second shaft; a printing frame; connections between said frame and disk for operating said frame; a severing mechanism; connections between said severing mechanism and disk for operating said mechanism; an inking means associated with said printing frame; connections between said first mentioned shaft and said inking means for operating the latter and tube forming mechanism associated with said foregoing mentioned parts, substantially as described.

38. In a machine for making paper cartons, the combination of a power distributing shaft; a paper feeding means; connections between said shaft and paper feeding means; a printing frame; a severing means for the paper; connecting means comprising a disk between said second shaft and said printing frame; means for applying glue to said paper; connections between said power distributing shaft and said glue applying means; a slotted guide; pivoted fingers in said guide; and tube forming means associated with said guide, substantially as described.

39. In a machine for making paper cartons, the combination of a power distributing shaft; a paper feed means; connections between said shaft and said paper feed means comprising gears and a second shaft; a reciprocating printing frame; a reciprocating severing mechanism for the paper; connections comprising a disk between said second shaft and said printing frame; lever connections between said severing mechanism and said disk; a glue applying means comprising

ing a reciprocating roll for said paper; connections comprising a cam and a lever between said power distributing shaft and said reciprocating roll; a slotted guide; pivoted 5 supporting fingers in said guide; longitudinally extending supports in said guide; and tube forming means associated with said guide, substantially as described.

40. In a paper tube machine, the combination of a main power shaft; a second power shaft; gear connections between said shafts; a power distributing shaft; gear connections between said second shaft and said power distributing shaft; a plurality of tube 10 winding mandrels; operating connections between said second shaft and said mandrels; means for feeding paper to said mandrels; and gear connections between said power 15 distributing shaft and said paper feeding shaft; means for feeding paper to said mandrels, substantially as described.

41. In a paper tube machine, the combination of a main power shaft; a second power shaft; gear connections between said shafts; a power distributing shaft; gear connections 25 between said second shaft and said power distributing shaft; a plurality of tube winding mandrels; operating connections between said second shaft and said mandrels; means for feeding paper to said mandrels; gear connections between said power 30 distributing shaft and said paper feeding means; means for printing on said paper before it reaches said mandrels; and connections between said power distributing shaft and said printing means, substantially as described.

42. In a paper tube machine, the combination of a main power shaft; a second power shaft; gear connections between said shafts; a power distributing shaft; gear connections between said second shaft and said power distributing shaft; a plurality of tube 40 winding mandrels; operating connections between said second shaft and said mandrels; means for feeding paper to said mandrels; gear connections between said power 45 distributing shaft and said paper feeding means, substantially as described.

power distributing shaft and said paper feeding means; means for severing said paper into predetermined lengths; and connections between said power distributing shaft and 50 said severing means, substantially as described.

43. In a paper tube machine, the combination of a main power shaft; a second power shaft; gear connections between said shafts; a power distributing shaft; gear connections between said second shaft and said power distributing shaft; a plurality of tube 55 winding mandrels; operating connections between said second shaft and said mandrels; means for feeding paper to said mandrels; gear connections between said power distributing shaft and said paper feeding means; means for applying glue to said paper; and connections between said power 60 distributing shaft and said glue applying means, substantially as described.

44. In a paper tube machine, the combination of a main power shaft; a second power shaft; gear connections between said shafts; a power distributing shaft; gear connections between said second shaft and said power distributing shaft; a plurality of tube winding mandrels; operating connections between said second shaft and said mandrels; 70 means for feeding paper to said mandrels; gear connections between said power distributing shaft and said paper feeding means; means for applying glue to said paper; connections between said power distributing shaft and said glue applying means; means for forcing said paper into contact with said mandrels; and connections between said power distributing shaft and said paper forcing means, substantially as 75 described.

In testimony whereof, I affix my signature, in presence of two witnesses.

GEORGE W. BEADLE.

Witnesses:

W. S. REED,
H. S. RODGERS.
